UNITED STATES PATENT OFFICE.

JULIUS SCHMIDT, OF LUDLOW, KENTUCKY.

LUBRICATING-CAN.

SPECIFICATION forming part of Letters Patent No. 696,501, dated April 1, 1902.

Application filed December 17, 1901. Serial No. 86,218. (No model.)

To all whom it may concern:

Be it known that I, JULIUS SCHMIDT, a citizen of the United States, and a resident of Ludlow, in the county of Kenton and State of Kentucky, have invented certain new and useful Improvements in Lubricating-Cans; and I do declare the following to be a clear, full, and exact description thereof, attention being called to the accompanying drawings, 5 with the reference-numerals marked thereon, which form also a part of this specification.

This invention relates to improvements in lubricating-cans in form of hand-oilers used for applying lubricating-oil and combining in 15 one implement the vessel or can which contains the oil and the means for causing the same to discharge and for guiding and directing such discharge to the particular parts and locations where the lubricant is to be applied.

The invention consists of certain improvements in details of construction, as hereinafter shown and described, and whereby the manufacture of the entire device is simplified 25 and its construction rendered more reliable and compact.

In the following specification, and particularly pointed out in the claims at the end thereof, is found a full description of the invention, together with its manner of use, parts, and construction, which latter is also illustrated in the accompanying drawings, in which—

Figure 1 shows in side elevation the oiler 35 in use. Fig. 2 is another side elevation of the same, showing it in a plane viewed at right angles to the view of the preceding figure. Fig. 3 is part of a vertical central section of the oiler viewed on a plane as shown 40 in the preceding figure. Fig. 4 is part of an elevation with the side partly broken away. Fig. 5 is a top view of the lower part of the oiler. Fig. 6 is a vertical section through the vented plug, enlarged. Fig. 7 is an enlarged detail view of the combined spout-coupling and valve-seat, the same being shown in vertical section. Fig. 8 is a detail view of the rock-shaft and connected rocker-arm whereby the valve in the spout is operated.

The lower part of the oiler serves as a reservoir to hold the oil, being the oil-can proper, and is of cylindrical shape as to its lower

part 10 and of conical shape 11 above the same. 12 is the spout connected at the apex of this conical part, with its discharge-nozzle 55 13 straight or curved, as shown in Fig. 1.

14 is the handle whereby the implement is held while used in various positions to apply oil—as, for instance, shown in Fig. 1. Immediately above it is the fill-inlet, the opening 15 being in the conical part 11 and surrounded by a fill-tube 16, the upper end of which is closed by a screw-plug 17. For its manipulation this latter is provided with a knob 18, both being of sheet metal and hollow. The knob is made in two sections joined to each other by a seam *a*, the joining edges being so shaped as to merely overlap each other sufficiently to keep the upper section in place on the lower one to hold this plug 60 closed and to prevent the outlet from becoming open. This seam is, however, not sufficiently tight to exclude air, and by admitting the same the plug as so constructed provides for the necessary vent to permit the 65 oil to discharge from the nozzle. To prevent oil from entering this hollow plug and its knob when the device is held in a position—as, for instance, shown in Fig. 1—whereby it would obstruct ingress of air 70 through the open seam at *a* and also ooze out therethrough, I provide a hollow conical extension 19, depending from the under side of the hollow screw-plug and in open communication therewith. The air admitted through 75 seam *a* escapes into the interior of the reservoir through a small opening at the pointed end 21 of this conical extension. This opening, while sufficiently large for air-admission, does not permit escape of oil, which, being 80 thick and viscous, does not readily enter such a small opening. Escape of oil from the nozzle when no discharge is intended is normally prevented by a valve 22, mounted at the upper end of a rod 23 and seated against a valve-seat 24. This latter is contained in a cast-metal member, serving at the same time as a coupling 25 between spout and nozzle for holding one to the other. Where the nozzle is removably connected to permit interchange 85 90 95 100 with other ones of different shape or size or removal for cleaning, this coupling consists of two complementary parts, as shown in Figs. 1 and 3, and joined by a screw connec-

tion—one part being attached to the end of the spout, the other to the contiguous end of the nozzle. Valve-seat 24 is contained in the part attached to the spout. When the nozzle is not detachable, said coupling is in one piece only, as shown in Figs. 2 and 7, and serves then simply as a soldering-coupling, uniting spout and nozzle, since these two parts being of sheet metal are not readily made in one piece.

20 Valve 22 is held normally to its seat by a spring 26, attached with one end to the inside of the can and with its other to a rocker-arm 27, projecting from a rock-shaft 28 and to which rocker-arm rod 23 attaches, there being a lug 29 provided for such purpose. Rock-shaft 28 is supported in two bearings 31 and 32. The first, intended to support the inner end of the rock-shaft, is attached to 25 and projects from the inside of the conical part 11 of the oil-reservoir. The other, being a tube, is attached opposite thereto, also to part 11, passing through the same, however, and projecting inwardly, as well as outwardly, 30 therefrom.

33 is a shoulder on the rock-shaft, which may also be produced by reducing part of such shaft, and this latter is kept in position lengthwise by this shoulder and by arm 27, 35 which bear each against the opposite inner ends of the shaft-bearings, thus holding the shaft immovable lengthwise, but free for rotation.

The outer end of shaft 28 projects beyond 35 tube 32, and the operating-lever handle 34 is affixed to this projecting end. That part of the shaft within tube 32 is closely fitted thereto, and the contacting surfaces between shoulder 33 and the inner edge of tube 32 are fitted 40 to each other by means of a ground joint, so that any escape of oil at the point where the rock-shaft passes to the outside is prevented without the use of stuffing-boxes, packing, or washers, all of which parts add to the manufacturing expenses and are not effective toward preventing leakage unless constantly attended to and repacked. There may also be a ground joint at the outside and between the outer end of tube 32 and the hub of lever-handle 34, which latter serves to hold the 45 members forming this ground joint in contact. The shaft is also held lengthwise in position between shoulder 33 and the lever-handle 34. It will now be seen that for purposes of effecting discharge of oil it is only necessary to depress the lever-handle, (see dotted lines in Figs. 2 and 3,) which is done by the thumb of the hand having hold of handle 14 of the implement, as shown in Fig. 1, 50 and the parts are so located that this latter handle serves as a stop, as shown in dotted lines in Fig. 2, to any further movement of operating-handle 34 as soon as the same has been sufficiently depressed to open valve 22. 55 This operation and opening of the valve need not take place until the nozzle is placed at the exact point where the oil is wanted, so that

any premature discharge of oil from the tipped can is prevented and deferred until the nozzle is in proper position. The discharge may 70 be instantly stopped equally as well, notwithstanding the tipped position of the can, and does not continue until this latter is restored to its upright position, all of which saves oil 75 and prevents spattering of the same over parts and places where it is not wanted.

In the practical construction of this device the inner end of shaft 28 must be placed first into the previously-attached bearing 31, and the other bearing 32 cannot be permanently 80 connected to the conical part 11 until the shaft is in position within the two bearings.

Having described my invention, I claim as new—

1. In a hand-oiler, the combination of an 85 oil-reservoir, an outlet-spout with a discharge-nozzle, a valve to control such discharge, an inlet-opening, a fill-tube surmounting the same, a hollow screw-plug to close this latter having a hollow knob consisting of two sections on its upper side and a hollow conical extension on its under side which extends into the oil-reservoir, all these parts in open communication with each other, an air-inlet between the two sections of the hollow knob and 95 an additional one in the lower pointed end of its conical extension.

2. In a hand-oiler, the combination of an 100 oil-reservoir, an outlet-spout with a discharge-nozzle, a valve to control such discharge, an inlet-opening, a fill-tube surmounting the same, a hollow screw-plug to close this latter and a hollow knob for its manipulation above the same and in open communication therewith, such knob being in two sections connected in a manner to permit access of air at 105 the joint between them, thus providing the requisite air-vent.

3. In a hand-oiler, the combination of an 110 oil-reservoir, a fill-inlet for the same, a nozzled outlet-spout, a valve-seat therein, a valve for it, a rocker-arm to which this valve is connected, a spring for keeping the valve normally seated, a rock-shaft for the rocker-arm, a shoulder 33 thereon, bearings to support 115 this rock-shaft extending from opposite sides inwardly and with their inner ends in contact, one with the rocker-arm and the other with shoulder 33 whereby in conjunction with such rocker-arm and said shoulder the rock-shaft is longitudinally held in position between the opposite inner ends of its bearings and means to manipulate this rock-shaft.

4. In a hand-oiler, the combination of an 120 oil-reservoir, a fill-inlet for the same, a nozzled outlet-spout, a valve-seat therein, a valve for it, a rocker-arm to which this valve is connected, a spring for keeping the valve normally seated, a rock-shaft for the rocker-arm, a bearing 31 to support the inner end of the 125 rock-shaft, a tubular bearing 32 to support the outer end which projects beyond this bearing, a shoulder 33 on the rock-shaft and in contact with the inner end of bearing 32, there

being a ground joint between these two parts and an operating-handle on the projecting part of the rock-shaft, the hub of which is in contact with the outer end of bearing 32, there-
5 by holding the members forming the ground joint at the inner end of said bearing in contact with each other.

In testimony whereof I hereunto set my hand in the presence of two witnesses.

JULIUS SCHMIDT.
